(57) **CLAIM**

The ornamental design for a headset earcup adapter, as shown and described.

DESCRIPTION

FIG. 1 is a top, right, front isometric view of a headset earcup adapter;

FIG. 2 is a bottom, left, back isometric view of the headset earcup adapter shown in FIG. 1;

FIG. 3 is a front view of the headset earcup adapter shown in FIG. 1;

FIG. 4 is a right side view of the headset earcup adapter shown in FIG. 1;

FIG. 5 is a left side view of the headset earcup adapter shown in FIG. 1;

FIG. 6 is a top view of the headset earcup adapter shown in FIG. 1; and,

FIG. 7 is a bottom view of the headset earcup adapter shown in FIG. 1.

The broken lines shown in the drawings represent portions of the headset earcup adapter that form no part of the claimed design.
